UNITED STATES PATENT OFFICE.

CHARLES L. JOHNSON, OF MORRISVILLE, PENNSYLVANIA, ASSIGNOR OF ONE-HALF TO
NEWTON B. JOHNSON, OF MORRISVILLE, PENNSYLVANIA.

WINDOW-SASH BOWER.

1,253,180.

Specification of Letters Patent.

Patented Jan. 8, 1918.

Application filed May 16, 1916. Serial No. 97,879.

To all whom it may concern:

Be it known that I, CHARLES L. JOHNSON, a citizen of the United States, residing at Morrisville, in the county of Bucks and 5 State of Pennsylvania, have invented new and useful Improvements in Window-Sash Bowers, of which the following is a specification.

This invention relates to builders' hardware, and more especially to bowers for sashes or similar swinging members hinged within other members; and the object of the same is to produce a device of this character having means for positively locking 10 the swinging member in various positions excepting that it will not lock the same when closed. For this latter purpose a separate latch or lock is desirable, and obviously this may not work when the swinging member is in any other position than closed. For details, reference is made to the following specification.

In the accompanying drawings:

Figure 1 is a vertical section through a window and an edge elevation of one swinging sash bowed outward by means of my invention, Figs. 2 and 3 are enlarged horizontal and vertical sections through the side rail of the swinging sash and the spring 30 bolt for locking the bower thereto, and Fig. 4 is a perspective detail of one of the pivot plates showing the bower across it in dotted lines.

Similar reference characters indicate corresponding parts throughout the several views of the drawings.

Referring to the drawings in detail, A designates generally a window frame which is of the ordinary well known construction 40 having the intermediate or parting strip 10 and guide strips 11, respectively, at each side thereof, as usual, for the slideable reception of the upper and lower main sashes 12 and 13 respectively, which can be raised 45 and lowered in the ordinary well known manner.

In each frame of the upper and lower sashes is mounted an auxiliary or supplemental swinging sash 14 which, together 50 with the main or sliding sash frame, is rabbeted, as at 15, for the tight fitting of the swinging sash 14 within the main or sliding sash to render the same weather-tight when the swinging sash is closed.

Each swinging sash 14 has mounted there- 55 in a sash pane or glass 16, as usual, and countersunk within opposite outer side edges of the swinging sash 14 to lie flush with the said edges are pivot plates 17 which are located substantially centrally of the said 60 swinging sash and are formed with headed pivots 18 which engage and work within slots 19 formed longitudinally in hanger arms 20 whose upper ends are mounted on pivots 21 in the opposite sides of each main 65 or sliding sash at the inner edges thereof, the said inner edges of the sides of the main or sliding sash being cut away in correspondence with the length of the arms 20 to accommodate the same when the swinging sash 14 is closed so that the said arms 20 will lie flush with the inner edges of the main or sliding sash. Each main or sliding sash has fitted in the side or vertical rails thereof suitable hand-released latch 70 devices 22 which serve to lock the swinging sash 14 closed to prevent the opening thereof from the outside of the window for intrusion. 75

Mounted in the side or vertical rails of 80 each swinging sash 14 are locking bolts 23 which work through apertures 17' in the pivot plates 17 for positive engagement with any one of a series of apertures or holes 24 formed in each hanger arm 20 alongside 85 its slot 19 so as to lock the swinging sash 14 in angular adjusted position and at any desired inclination relative to the main or sliding sash. By preference the bolt is normally projected through the medium of 90 a coiled expansion spring 24' operating upon a shoulder 25 on said bolt and confined within a recess 26 formed in the vertical or side rail of the sash 14 so that in this manner the bolt will be positively 95 moved to locking position for the fastening of the movable sash in adjusted position. The bolt 23, at its inner end, is formed with a knurled head 27 which permits the convenient manipulation thereof for the re- 100 tracting of the same against the resistance of the spring 24' to release the bolt to permit the movement of the swinging sash.

An important feature of the present invention is the fact that one latch can not 105 be operated except when the other is idle. The bolt 23 holds the sash open, and at this time the latch 22 obviously can not work.

The latter holds the sash closed, and at this time the tip of the latch-bolt 23 has passed the uppermost hole 24 and has been carried over the end of the slot 19 because the 5 arm 20 now hangs across the plate 17 as seen in dotted lines in Fig. 4, and the bolt 23 is directly above the pivot 18. Hence it is impossible for the action of one latch to prevent the action of the other, and it 10 is never necessary to actuate more than one pair of latches before moving the sash.

It will be noted that when the sash 14 is swung to open position the lower edge thereof rests upon the main or sliding sash and 15 is hingedly supported but without the necessity for hinges, and in this manner the said swinging sash is removably mounted therein. When the swinging sash is open it enables the easy cleaning of the pane of glass 20 16 therein without necessitating the cleaner assuming hazardous positions at the outside of the window as is usual.

From the foregoing description, taken in connection with the accompanying draw-

ings, the construction and operation of my 25 window sash construction will be readily apparent and, therefore, a more extended explanation has been omitted.

Having thus described my invention, I 30 claim:

The combination with a frame member, and a swinging member hingedly mounted at its lower end therein; an arm standing between the side bars of the members when closed and having a longitudinal slot and 35 a series of holes alongside the same, means for pivoting one end of the arm to one member, a plate on the other member having a pin sliding in said slot and an aperture adapted to register successively with said 40 holes as this member is moved and to pass over the end of the slot as it is closed, and a bolt in the swinging member whose tip is adapted to project through said aperture, for the purpose set forth.

In testimony whereof I affix my signature.

CHARLES L. JOHNSON.
